DANIEL HAYES MURPHY, OF WEST HARTFORD, CONNECTICUT

MASSAGE MACHINE

Application filed July 28, 1930. Serial No. 471,131.

This invention relates to an apparatus which is particularly adapted for massaging the abdominal portions of the body.

The object of the invention is the production of a relatively simple and inexpensive apparatus that may be used by professional masseurs or for self treatment by anyone, and which will roll and stretch the abdominal muscles of the patient in such manner that 10 the natural function of the colon will be effectively assisted and facilitated.

In the embodiment of the invention illustrated there is a casing shaped to approximately fit the abdomen of the patient and 15 containing a motor and an applicator designed to be rotated by the motor in the direction of the normal action of the colon, the contact elements of the applicator being in the nature of rotatable balls of substantial size 20 that may be adjusted radially of the applicator to meet the conditions of persons of various sizes, and that are sufficiently spaced to enable the abdominal walls to regain normal position after one ball has acted before the 25 next ball acts on the same locality, which action produces a running muscle wave that will manipulate the colon in a manner similar to that resulting from the use of the human hand, means being provided to eliminate irritation of the skin by the balls.

In the accompanying drawings Fig. 1 shows a side elevation of the apparatus with a portion of the casing broken away. Fig. 2 is a front view. Fig. 3 is a rear view. Fig. 4 is a side elevation with the casing and the applicator cut in diametrical section.

The casing of the apparatus has a circular base 1 with a wall 2 extending from its periphery. This wall on two diametrically opposite sides is higher than on the diametrically opposite sides at right angles thereto so that its edge 3, which is curled outwardly, will conform more or less to the configuration of the abdomen of the average patient.

An electric motor 4 is secured to the back 40 of the base and on the armature shaft 5 of the motor is a worm 6. This worm meshes with a worm wheel 7 fastened to an arbor 8 that is mounted in a bearing pillar 9 which is attached to the back of the base. A shell 10, pro-

vided on its exterior with handles 11, is fastened to the back of the base so as to enclose the motor and the worm and worm wheel. The motor is designed to be connected by a plug 12 with any convenient outlet socket and the current is controlled by a switch 13 located on the shell adjacent to one of the handles.

The rotatable applicator has a circular plate 14 with a central axle 15 that is mounted to turn in a bushing 16 which is inserted in an opening in the base. The applicator is held in place by a disk 17 that is fastened to the inner end of the axle, and anti-friction bearings 18 are located around the axle between the inner face of the applicator plate 60 and the outer face of the base.

Secured to the inner face of the applicator plate is an annular gear 19 that is engaged by a pinion 20 which is fastened to the end of the arbor 8 of the worm wheel 7. This gear 70 may be made of compressed fiber or similar anti-noise material so that the gear and pinion will run noiselessly.

Mounted on the outer face of the applicator plate are yokes 21 which have arbors 22 at their outer ends that support the means for manipulating the abdominal muscles, which means may be in the form of rounded shoes or balls 23. The yokes have stems 24 which are clamped against the outer face of the applicator plate by a disk 25 that is secured in place by a screw 26. Upon loosening the screw and releasing the clamp disk the stems of the yokes may be moved in or out so that the radial distance of the balls from the center of the applicator may be adjusted to accord with the size of the patient. Studs 27 are arranged to project from the applicator plate each side of the yoke stems so as to hold them firmly and ensure their rotation with the applicator plate. Three yokes and balls are illustrated. An extra set of studs may be projected from the applicator plate so that one of the three yokes and balls 85 may be removed and another may be taken from the place shown and located to provide two yokes and balls 180° apart instead of three yokes and balls 120° apart, as indicated in Fig. 2 of the drawings.

To prevent the balls from irritating the 100

skin of the patient by friction resulting from direct contact, a cap or flexible diaphragm 29 of fabric or other suitable material, may be placed over the balls and its edge gathered in 5 the curled edge 3 of the wall of the base and held in place by a cord 30, as indicated in Fig. 4.

In using the apparatus illustrated, after 10 the balls have been adjusted toward and from each other according to the size of the patient to be treated, the applicator is applied to the abdomen of the patient who is in a prone position face up, the handles grasped and the switch thrown starting the motor, which, 15 through the worm, worm wheel, pinion and annular gear, rotates the applicator plate, thus causing the applicator balls to roll around.

The patient holds the device against the 20 abdomen and the balls, which are of substantial size and widely separated, are revolved from the motor by the mechanism described in such manner as to flex the abdominal muscles with a continuous long wave motion 25 in the direction of the normal action of the colon. The weight of the apparatus including the motor, is utilized in obtaining the desired pressure of the applicator against the abdominal wall so that a deep and very effective 30 massage can be obtained in the direction of the normal action of the colon, and this is assured as the side wall of the casing fitting the body, tends to retain the normal shape of the abdomen and prevent it from flattening 35 out. If the diaphragm is used this massage is accomplished without irritating the skin of the patient.

The invention claimed is:

1. An abdominal massage machine 40 comprising a cup shaped casing having a circular side wall with its outer edge curved to fit across the front and down the sides of the abdomen, an applicator plate mounted to rotate within the casing and having forwardly 45 projecting studs, a clamp disk removably fastened to said plate, yokes retained between said studs by said disk, applicators carried by said yokes, a gear fastened to the inner face of said plate, an electric motor secured to the back of the casing, gearing connecting the motor with said gear, and a shell enclosing 50 the motor and gearing.

2. An abdominal massage machine 55 comprising a cup shaped casing having a circular side wall with its outer edge curved to fit across the front and down the sides of the abdomen, a circular applicator plate mounted to rotate within the casing, yokes radially adjustable on the outer face of said plate, means 60 clamping the yokes to said plate, balls carried by said yokes, a gear fastened to the inner face of said plate, an electric motor secured to the back of the casing, gearing connecting the motor with said gear, and a shell enclosing 65 the motor and gearing.

3. An abdominal massage machine comprising a cup shaped casing having a circular side wall with its outer edge curved to fit across the front and down the sides of the abdomen, a circular applicator plate mounted to rotate within the casing, yokes having stems radially located on the outer face of 70 said plate, a central disk clamping said stems to the plate, balls rotatably mounted on said yokes, a gear fastened to the inner face of said plate, a pinion engaging said gear, an electric motor secured to the back of the casing, gearing connecting the motor with said pinion, and a shell enclosing the motor and gearing. 75

4. An abdominal massage machine comprising a cup shaped casing having a circular side wall with its outer edge curved and curled to fit across the front and down the sides of the abdomen, a circular applicator plate mounted to rotate within the casing, yokes radially adjustable on the outer face of 80 said plate, means clamping the yokes to said plate, balls carried by said yokes, a gear fastened to the inner face of said plate, an electric motor secured to the back of the casing, gearing connecting the motor with said gear, a shell enclosing the motor and gearing, and a flexible diaphragm with its edge fitted over and retained by the curled edge of the casing 85 and enclosing the applicator. 90

5. An abdominal massage machine comprising a cup-shaped casing having a circular side wall, an applicator plate mounted to rotate within the casing and having forwardly projecting studs, a clamp disk removably fastened to said plate, yokes retained between 100 said studs by said disk, applicators carried by said yokes, a gear fastened to the inner face of said plate, an electric motor secured within the casing, and gearing connecting the motor with said applicator gear. 105

6. An abdominal massage machine comprising a cup-shaped casing having a circular side wall, an applicator plate mounted to rotate within the casing, yokes having stems radially located on the outer face of said plate, a central disk clamping said stems to 110 said plate, applicators rotatably mounted on said yokes, a gear attached to the inner face of said plate, a pinion engaging said gear, an electric motor secured within the casing, and gearing connecting the motor with said pinion. 115

7. An abdominal massage machine comprising a cup-shaped casing having a circular side wall with a curled flange on its outer edge, an applicator plate mounted to rotate within the casing, yokes radially adjustable on the outer face of said plate, means clamping the yokes to said plate, applicators carried by said yokes, a gear fastened to the inner face of said plate, an electric motor secured within the casing, gearing connecting the motor with said applicator gear, and a flex- 120

ible diaphragm with its edge fitted over and retained by the curled edge of the casing.

8. An abdominal massage machine comprising a cup-shaped casing having a circular wall, an applicator plate mounted to rotate within the casing, yokes having stems located on the outer face of said plate, detachable means clamping said stems to said plate, applicators rotatably mounted on said yokes, a gear attached to the inner face of the plate, a pinion engaging said gear, and an electric motor secured within the casing and connected to rotate said pinion.

9. An abdominal massage machine comprising a cup-shaped casing having a circular side wall, an applicator plate mounted to rotate within the casing, yokes movably applied to the outer face of said plate, applicators rotatably mounted on said yokes, means detachably clamping the yokes in position on the face of said plate, said means permitting radial adjustment of and variations of angular relation to each other of the yokes on said plate, an electric motor enclosed within the casing, and gearing connecting the motor with said plate.
